(57) **CLAIM**

The ornamental design for a telescope, as shown and described.

DESCRIPTION

FIG. 1 is a front, top, and right side perspective view of a first embodiment of a telescope showing my new design; FIG. 2 is a rear, top, and left side perspective view thereof; FIG. 3 is a front view thereof; FIG. 4 is a rear view thereof; FIG. 5 is a top plan view thereof; FIG. 6 is a bottom plan view thereof; FIG. 7 is an enlarged right side view thereof; FIG. 8 is an enlarged left side view thereof;

FIG. 9 is a front, top, and right side perspective view of a second embodiment of a telescope showing my new design; FIG. 10 is a rear, top, and left side perspective view thereof; FIG. 11 is a front view thereof;

FIG. 12 is a rear view thereof;

FIG. 13 is a top plan view thereof;

FIG. 14 is a bottom plan view thereof;

FIG. 15 is an enlarged right side view thereof; and,

FIG. 16 is an enlarged left side view thereof.

The features shown in broken lines in the drawings depict environmental subject matter only and form no part of the claimed design. The dash-dotted lines denote the boundary of

the claim and form no part of the claimed design.
